UNITED STATES PATENT OFFICE

2,531,316

MULTIPLE FUEL BURNER

John S. Zink, Tulsa, Okla.

Application August 9, 1946, Serial No. 689,575

2 Claims. (Cl. 158—11)

1

This invention relates to improvements in burners, and more particularly to improvements in gas and/or oil burners.

The primary object of the invention is to improve burner structures of the types disclosed in Patents 1,513,260; 1,715,051; 2,204,719 and 2,344,936.

In accordance with the invention, a gas burner having a spider and provided at its center with a passageway for the reception of an oil burner or an auxiliary or pilot gas burner, is provided at its central portion with a frusto-conical front cavity which may be an integral part of the spider or may be attached thereto. Where the cone is cast integrally with the spider, the improved contour for flow of gas or gas-air mixture to the spider arms lessens pressure drop resulting in increased primary air and improved operation of the burner. Where the cone is made separately and attached to the spider, it improves the oil burner operation.

The invention will be understood from the accompanying drawings, in which:

Fig. 1 is a front elevation of one form of the improved burner shown arranged in an opening in a furnace wall.

Fig. 2 is a longitudinal vertical sectional view of the same, taken on the line 2—2 of Fig. 1.

Referring to the embodiment of the invention illustrated in Figs. 1 and 2, 5 designates a fragment of a furnace wall having a port 6 leading to the combustion chamber (not shown) of the furnace.

A metallic mounting ring 7 is fixedly associated with the port and, in turn support a yoke 8 to hold a horizontally disposed gaseous fuel tube 9. The yoke may be of the type disclosed in my prior patents, some of which are mentioned above, as such a yoke permits the ready insertion or removal of the spider 10, supported by conduit 9.

An internal tube 11 is arranged co-axially within, and spaced from the external tube 9, to provide an annular passageway 12 through which gas or a gas-air mixture may travel to the spider. As in some of my prior patents, the spider is provided with hollow radial arms 13 and ports 14, 15, for the discharge of the gas or gas-air mixture into the combustion chamber of the furnace. The chambers 16 of the spider communicate with the passageway 12, and in accordance with the present invention, a frusto-conical wall 17 is arranged at the central portion of the spider and extends inwardly at its smaller end to merge with the conduit 11 so as

2

to provide a substantially conical recess arranged rearwardly of the front face 18 of the spider. Such cavity or recess is designed to cooperate with an auxiliary burner 19 which is inserted into the burner through the conduit 11 and is preferably mounted on the discharge end of a pipe 20. The inlet end portion of the latter is provided with a seal 21 to prevent air from entering the inlet end of the conduit 11, and means 10 is connected to the inlet end of the pipe 20 for introducing oil at 22 and steam at 23, in the event the burner 19 is used with oil fuel. On the other hand, if the burner 19 is an auxiliary gas burner or a pilot burner, it is obvious that gas 15 will travel to the same through the pipe 20.

It will be observed that the frusto-conical wall 17 is bi-angularly shaped for the purpose of providing a cavity so that the fuel issuing from the auxiliary burner ports 31 may expand without 20 impinging on the inner surface or surfaces of the frusto-conical wall. In other words, the frusto-conical wall portion 32 adjacent the base flares away from the axis of the conical member at a greater angle than the wall portion 33 adjacent the auxiliary burner 19. An annular flared member 34 connects the end of the fuel supply tube 9 to the spider arms 13. This flared wall 34 is substantially parallel to the wall portion 33 of the frusto-conical member to thereby 30 reduce the resistance of the fuel supply passages and to facilitate the flow of the gaseous fuel to the hollow spider arms.

An air control means or plate 24 may be slidably mounted on the conduit 9 for controlling 35 the introduction of air for combustion, into the port 6.

In the use of the improved burner, I have found that if the auxiliary burner 19 is arranged within the frusto-conical cavity at the 40 smaller end of the wall 17, the air which passes between the arms of the spider will flow into 45 the mouth of the cone toward the auxiliary burner, as indicated by the arrows. Apparently, the cone inverts air flow to a point adjacent to the tip of the auxiliary burner, thus causing the latter to stay lit and the fuel therefrom to burn very steadily with a flame beginning immediately at the tip of the auxiliary burner. Furthermore, the frusto-conical wall acts to "streamline" the 50 entrance to the chambers 16 so that the gaseous fuel flows more evenly through the spider before discharging through the ports 14 and 15.

While I have disclosed what I now consider to be a preferred embodiment of the invention in 55 such manner that it may be readily understood

by those skilled in the art, it is manifest that changes may be made in the details disclosed without departing from the spirit of the invention, as expressed in the following claims.

What I claim and desire to secure by Letters Patent is:

1. In a multiple fuel burner, a spider including hollow radially disposed arms, each of said arms having discharge ports therein, a frusto-conical wall having a base portion and an apex portion, a conduit joining the apex portion of the frusto-conical wall, said base portion of the frusto-conical wall being connected to said hollow arms, an auxiliary burner head having ports therein spaced rearwardly of the base portion of the frusto-conical wall and substantially aligned with the apex portion of the frusto-conical wall, means extending through said conduit for supplying fuel to the auxiliary burner, means closing the conduit preventing air from moving through the conduit to the presence of the auxiliary burner, a fuel supply tube surrounding said conduit in spaced relation, and an annular flared portion carried by said tube surrounding the apex portion of the frusto-conical wall in spaced relation and joining said hollow arms for supplying fuel thereinto.

2. In a multiple fuel burner, a spider including hollow radially disposed arms, each of said arms having discharge ports therein, a frusto-conical wall having a base portion and an apex portion, a cylindrical conduit joining the apex portion of the frusto-conical wall and extending rearwardly

therefrom, said base portion of the frusto-conical wall being connected to the hollow arms of the spider, an auxiliary burner head having ports therein substantially aligned with the apex portion of the frusto-conical wall, a pipe extending through said conduit supporting the burner head and for supplying fuel to the auxiliary burner, means closing the conduit preventing air from moving forwardly through the conduit to the auxiliary burner, a fuel supply tube surrounding said conduit in spaced relation, and an annular flared portion carried by the fuel supply tube surrounding the apex portion of the frusto-conical wall in spaced substantially parallel relationship and connected to said hollow arms for supplying fuel thereinto.
